EAR COVERING

Lester D. Hames, 7600 Embassy Terrace,
Oklahoma City, Okla. 73108

Filed Nov. 17, 1969, Ser. No. 20,147

Term of patent 14 years

Int. Cl. D2—03

U.S. Cl. D2—259

FIG. 1 is a front elevational view of the ear covering showing my new design, as worn by an individual, the head of the individual being shown in dashed-lines for the purposes of illustration only.

FIG. 2 is an enlarged rear elevational view thereof.

FIG. 3 is a side elevational view thereof.

FIG. 4 is a side elevational view of the side opposite the side shown in FIG. 3.

FIG. 5 is a cross sectional view taken substantially along the lines 5—5 of FIG. 2.

FIG. 6 is an end elevational view taken from the left of FIG. 3.

FIG. 7 is an end elevational view taken from the right of FIG. 3.

I claim:

The ornamental design for an ear covering, as shown and described.
